Primary Examiner — Paula Greene(74) *Attorney, Agent, or Firm* — Rader, Fishman & Grauer PLLC(57) **CLAIM**

The ornamental design for an earphone, as shown and described.

DESCRIPTION

FIG. 1 is a perspective view of an earphone showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken line shown in dotted lines form no part of the claimed design; the broken lines shown in dashed lines define the bounds of the claimed design and form no part thereof.
